ABSTRACT OF THE DISCLOSURE

1-[2-(dimethylamino)-6,7-dimethoxy-4-quinazolinyl]-3-methylurea and similar 1-(2-amino-4-quinazolinyl)ureas are hypotensive agent. Reacting alkyl isocyanate with a 2-amino-4-(unsubstituted amino)quinazoline affords the 1-(4-quinazolinyl)-3-alkylureas; reacting a 2-amino-4-(unsubstituted amino)quinazoline with inorganic cyanate and hydrochloric acid affords the 1-(4-quinazolinyl)urea.

BACKGROUND OF THE INVENTION

This invention relates to novel chemotherapeutic agents; in particular, it relates to certain novel quinazolinylureas which are useful as hypotensive agents.

SUMMARY OF THE INVENTION

The novel compounds of the instant invention are quinazolinylureas of the formulae

wherein

R_1 and R_2 are each selected from the group consisting of hydrogen, alkyl having from 1 to 5 carbon atoms, alkenyl having from 3 to 5 carbon atoms, hydroxylalkyl having from 2 to 5 carbon atoms, phenyl, benzyl, phenylethyl, 2-furfuryl, 2,2,2-trifluoroethyl and cycloalkyl having from 3 to 8 carbon atoms;

R_3 is H or alkyl having from 1 to 6 carbon atoms;
 R_4 and R_5 are each selected from hydrogen and alkoxy having from 1 to 3 carbon atoms, at least one of R_4 and R_5 being alkoxy:

Z is selected from the group consisting of morpholino, 1-azacycloheptyl, 1-azacyclooctyl;

piperazine of the formula:

where Y is selected from the group consisting of hydrogen, alkyl having from 1 to 5 carbon atoms, hydroxy-alkyl where alkyl has from 2 to 5 carbon atoms, alkanoyl having from 2 to 7 carbon atoms, allyl, propargyl, 2-methylallyl, phenyl, benzyl, benzoyl, halo-benzoyl and halophenyl where halo is chloro or bromo,

2

trifluoromethylphenyl, methoxyphenyl, methylphenyl, methylbenzoyl, methoxybenzoyl, trifluoromethylbenzoyl, furoyl, benzofuroyl, thenoyl, pyridinecarbonyl, 3, 4,5-trimethoxybenzoyl, carboxylic acid alkyl ester where alkyl has from 1 to 6 carbon atoms, carboxylic acid alkenyl ester where alkenyl has from 3 to 6 carbon atoms; iperidino of the formula:

where X is selected from the group consisting of hydrogen, alkyl having from 1 to 5 carbon atoms, alkoxy having from 1 to 4 carbon atoms, hydroxy, hydroxy-alkyl where alkyl has from 2 to 5 carbon atoms, phenyl and benzyl when X' is hydrogen, and X is carboxylic acid alkyl ester where alkyl has from 1 to 6 carbon atoms when X' is phenyl.

These quinazolinylureas are effective hypotensive agents and may be administered for this purpose as the free base or pharmaceutically-acceptable acid addition salt, either alone or with a pharmaceutically-acceptable carrier.

DETAILED DESCRIPTION OF THE INVENTION

The instant compounds wherein R_3 is alkyl are readily prepared from 4-aminoquinazolines of the formulae

wherein R_1 , R_2 , R_4 , R_5 and Z are as aforesaid. These 4-aminoquinazolines may be obtained by methods disclosed in U.S. patent application Ser. No. 555,704, filed June 6, 1966 (now abandoned).

June 6, 1966 (now abandoned). Treating said 4-aminoquinazolines with alkyl isocyanate $R_3\text{-NCO}$ results in the formation of the desired compound of Formula I or II wherein R_3 is alkyl containing up to 6 carbon atoms. For best results, a substantial excess of the alkyl isocyanate should be used. The reaction is preferably conducted in a pressure vessel when the alkylisocyanate has a low boiling point, for example methyl isocyanate, in order to prevent loss of this reagents. With higher boiling isocyanates, the need for a pressure vessel is not as urgent and it may be dispensed with entirely where the boiling point is sufficiently high. Common reaction-inert organic solvents may be used, such as benzene, toluene, pyridine and triethylamine. However, inasmuch as the reaction proceeds best in the presence of base, basic solvents such as pyridine and triethylamine are preferred. Neither reaction time nor temperature is critical. When using a pressure vessel, temperatures between room temperature and about 130° C. are effective; when a pressure vessel is not used, with higher alkyl isocyanates, temperatures between room temperature and reflux are appropriate. Reaction times up to about 24 hours are adequate; of course a higher reaction temperature will permit the use of shorter times without a loss of product. With methyl isocyanate, for example, running the reac-

tion for about 4-10 hours at about 100° C. has typically resulted in satisfactory yields.

The products are isolated from the reaction mixture by standard procedures familiar to those skilled in the art, for example, precipitation, removal of solvent, extraction and the like.

When compounds of Formulae I and II, wherein R_3 is alkyl, have R_1 or R_2 as hydrogen or R_1 , R_2 or Z containing a hydroxyl group, aforesaid reaction with alkyl isocyanate is not preferred since these substituents would be expected to react with the isocyanate reagent. A preferred synthesis of these compounds is the conversion of a 2-chloro-4-aminoquinazoline to 1-(2-chloro-4-quinazolinyl)-3-alkylurea by treatment with alkyl isocyanate, followed by replacement of the 2-chloro group with the specific amino group desired, according to the sequence

The various 2-chloro-4-aminoquinazolines are obtained by methods disclosed in aforesaid application Ser. No. 555,704. The reaction with alkyl isocyanate is conducted under the same conditions of time, temperature, pressure and substrate ratio as aforesaid treatment of 4-aminoquinazolines with alkyl isocyanate. The resulting 1-(2-chloro-4-quinazolinyl)-3-alkylurea is most easily converted to the various 1-(2-amino-4-quinazolinyl)-3-alkylureas by heating a solution or suspension of the chloro material with the appropriate amine, e.g. heating with ethylamine results in the formation of a 2-ethylamino-quinazoline. An ethanolic solution of the amine may conveniently be used for suspending the chloro material and temperatures between about 100° C. and 180° C. are adequate. Heating for up to about 24 hours is usually sufficient. The final material is easily isolated by evaporating the excess solvent and amine and recrystallizing the product.

Preparation of compounds of Formulae I and II wherein R_3 is hydrogen is accomplished by reacting a 2-amino-4-(unsubstituted amino)quinazoline with an inorganic cyanate and hydrochloric acid. Ammonium cyanate, sodium cyanate and potassium cyanate are suited for this purpose. At least equimolar amounts, with respect to the quinazoline, of cyanate and hydrochloric acid are preferably used, and more preferably, at least a 10% molar excess of each will be used.

The reaction is conveniently conducted by adding the reagents to an aqueous suspension of the quinazoline. Neither reaction time nor temperature is critical, and the reaction may be conducted between about room temperature and reflux, with the necessary time to obtain satisfactory yields being dependent upon the temperature. It has been found that warming the aqueous reaction mixture on a steam bath for one hour affords a satisfactory yield of the product, which may then be isolated and purified by standard techniques such as solvent removal, crystallization, extraction and the like.

Compounds of Formulae I and II wherein R_3 is hydrogen can also be prepared from aforesaid 2-chloro-4-aminoquinazolines when the reactivity of a particular amino moiety at the 2-position might interfere with the desired conversion, according to the sequence

The novel quinazolinylureas of the instant invention are effective hypotensive agents in animals, and are thereby useful in alleviating high blood pressure in hypertensive subjects. For this purpose, these compounds are administered by standard methods familiar to those skilled in the art. Preferred agents are those wherein R_4 and R_5 are each methoxy, in particular 1-[2-(4-{2-furoyl}-1-piperazinyl)-6,7-dimethoxy-4-quinazolinyl]-3-methylurea, 1-[2-(dimethylamino)-6,7-dimethoxy-4-quinazolinyl]-3-methylurea, 1-[2-(4-allyl-1-piperazinyl)-6,7-dimethoxy-4-quinazolinyl]-3-methylurea and 1-[2-(4-carboisobutoxy-1-piperazinyl)-6,7-dimethoxy-4-quinazolinyl]-3-methylurea.

The instant compounds may be conveniently administered in the form of pharmaceutically-acceptable salts. By "pharmaceutically-acceptable" is meant those salts which do not have substantially greater toxicity than the free compound. The pharmaceutically acceptable acid addition salts include salts of mineral acids such as hydrochloric, hydrobromic, hydroiodic, phosphoric, metaphosphoric, nitric and sulfuric acids, as well as salts of organic acids such as tartaric, citric, maleic, glycollic, gluconic, gulonic, succinic, arylsulfonic, e.g. p-toluenesulfonic acid and the like.

The pharmaceutically-unacceptable salts, while not useful for therapy, are valuable for use in the isolation and purification of these newly discovered compounds. Furthermore, they are useful for the preparation of the therapeutically valuable pharmaceutically-acceptable salts. Of this group, the more common salts include those formed with hydrofluoric and perchloric acids. Hydrofluoride salts are particularly useful for the preparation of the pharmaceutically-acceptable salts. The hydrochloride salts, for example, may be prepared by the solution of the hydrofluoride salts in hydrochloric acid and crystallization of the hydrochloride salt thereby formed.

It is necessary that the active ingredient from a proportion of the composition such that a suitable dosage form will be obtained. Obviously, several dosage unit forms may be administered at about the same time. Although compositions with less than 0.005% by weight of active ingredient might be used, it is preferred to use compositions containing not less than 0.005% of the active ingredient; otherwise the amount of carrier becomes excessively large. Activity increases with the concentration of the active ingredient. The composition may contain 10, 50, 75, 95 or an even higher percentage by weight of the active.

The person who administers the instant agents will determine the dosage which will be most suitable, and it will vary with the age, weight and response of the particular subject as well as with the nature and extent of the symptoms and the pharmacological characteristics of the particular agent to be administered. Generally, small doses will be administered initially, with a gradual increase in the dosage until the optimum level is determined. It will often be found that when the composition is administered orally, larger quantities of the active ingredient will be required to produce the same level as produced by a small quantity administered par-

enterally. In general, a dosage level within the range of from about 0.2 to about 50 mg. of active ingredient per kilogram of body weight, administered in single or multiple dose units, will effectively lower blood pressure. Of course, there can be individual cases where higher or lower dosage levels are desirable, and such are within the scope of this invention.

The following examples are given to more fully illustrate the present invention. It is understood that these examples are for illustrative purposes only and are not to be considered as the only manner in which the instant invention may be embodied.

EXAMPLE I

1-[2-(dimethylamino)-6,7-dimethoxy-4-quinazolinyl]-3-methylurea

To a solution of 2-dimethylamino-4-amino-6,7-dimethoxyquinazoline (4.84 g., 0.0195 mole) in 150 ml. of pyridine was added methyl isocyanate (20.6 g., 0.36 mole). The mixture was heated in a pressure vessel at 80° C. for 4 hours and then cooled in an ice bath. The resulting crystalline material was collected by filtration, washed with ether and dried to afford the desired product, 4.76 g. (80%), M.P. 260-263° C.

Analysis.—Calc'd for $C_{14}H_{19}N_5O_3$ (percent): C, 55.07; H, 6.27; N, 22.94. Found (percent): C, 55.39; H, 6.07; N, 22.95.

Analysis.—Calc'd for $C_{21}H_{24}N_6O_5$ (percent): C, 57.26; H, 5.49; N, 19.08. Found (percent): C, 56.88; H, 5.59; N, 19.00.

EXAMPLE III

5 Alkyl isocyanates are reacted with 2-dimethylamino-4-amino-6,7-dimethoxyquinazoline and 2-[4-(2-furoyl)piperazin-1-yl]-4-amino-6,7-dimethoxyquinazoline according to the procedures of Examples I and II to afford the following products:

- 10 1-[2-(dimethylamino)-6,7-dimethoxy-4-quinazolinyl]-3-ethylurea
 1-[2-(dimethylamino)-6,7-dimethoxy-4-quinazolinyl]-3-isopropylurea
 15 1-[2-(dimethylamino)-6,7-dimethoxy-4-quinazolinyl]-3-n-hexylurea
 1-[2-(4-[2-furoyl]-1-piperazinyl)-6,7-dimethoxy-4-quinazolinyl]-3-ethylurea
 20 1-[2-(4-[2-furoyl]-1-piperazinyl)-6,7-dimethoxy-4-quinazolinyl]-3-isopropylurea
 1-[2-(4-[2-furoyl]-1-piperazinyl)-6,7-dimethoxy-4-quinazolinyl]-3-n-hexylurea

EXAMPLE IV

The following 1-(2-amino-4-quinazolinyl)ureas are prepared in the same manner as Examples I-III with the appropriate 4-amino-quinazoline and isocyanate:

R_1	R_2	R_3	R_4	R_5
C_6H_5	C_6H_5	CH_3	CH_3O	CH_3O

EXAMPLE II

1-[2-(4-[2-furoyl]-1-piperazinyl)-6,7-dimethoxy-4-quinazolinyl]-3-methylurea

Methyl isocyanate (20.6 g., 0.36 mole) was added to a solution of 2-[4-(2-furoyl)piperazin-1-yl]-4-amino-6,7-dimethoxyquinazoline (7.67 g., 0.0195 mole) in 150 ml. of pyridine. The mixture was heated in a pressure vessel at 100° C. for 7 hours and then cooled in an ice bath. The resulting crystalline material was collected by filtration, washed with ether and dried to afford the desired product, 5.6 g. (63%), M.P. 240-243° C.

EXAMPLE V

1-[2-(4-methyl-1-piperazinyl)-6,7-dimethoxy-4-quinazolinyl]-3-methylurea

70 Methyl isocyanate (20.6 g., 0.36 mole) is added to a solution of 2-(4-methyl-1-piperazinyl)-4-amino-6,7-dimethoxy quinazoline (6.11 g., 0.0195 mole) in 150 ml. of pyridine. The mixture is heated in a pressure vessel at 100° C. for 7 hours and then cooled in an ice bath. The resulting precipitate is collected by filtration, washed with ether and dried to afford the desired product.

7
EXAMPLE VI

The following 1-(2-amino-4-quinazolinyl)ureas are prepared in the same manner as Example V using the appropriate 4-aminoquinazoline and isocyanate:

Z	R ₃	R ₄	R ₅

4-trifluoromethyl-1-piperazinyl	do	do	Do.

EXAMPLE VII

The following 1 - (6,7 - dimethoxy-4-quinazolinyl)-3-methylureas are prepared by the procedure of Example V;

50

55

EXAMPLE VIII
1-[2-(4-allyl-1-piperazinyl)-6,7-dimethoxy-4-quinazolinyl]-3-methylurea

60 The procedure of Example V was repeated using an equivalent amount of 2-[4-allyl-1-piperazinyl]-4-amino-6,7-dimethoxyquinazoline. The reaction was conducted at 100° C. for 4 hours to afford the desired product in 78.5% yield, M.P. 248-250° C.

65 *Analysis.*—Calc'd for C₁₉H₂₆N₆O₃ (percent): C, 59.05; H, 6.78; N, 21.75. Found (percent): C, 59.03; H, 6.62; N, 21.78.

EXAMPLE IX

1-[2-(4-carbisobutoxy-1-piperazinyl)-6,7-dimethoxy-4-quinazolinyl]-3-methylurea

70 The procedure of Example V was repeated using an equivalent amount of 2-(4-carbisobutoxy-1-piperazinyl)-4-amino-6,7-dimethoxyquinazoline. The reaction was conducted at 100° C. for 4 hours to afford the desired product in 48% yield, M.P. 241-243° C.

8

The following 1-(6,7-dimethoxy-4-quinazolinyl)-3-methylurea similarly prepared:

Analysis.—Calc'd for $C_{21}H_{30}N_6O_5$ (percent): C, 56.49; H, 6.77; N, 18.82. Found (percent): C, 56.39; H, 6.70; N, 18.83.

EXAMPLE X

(2-dimethylamino-6,7-dimethoxy-4-quinazolinyl)urea

To a suspension of 7.44 g. (0.3 mole) of 4-amino-2-dimethylamino-6,7-dimethoxyquinazoline in 30 ml. of warm water is added, with stirring, 2.75 ml. (0.33 mole) of concentrated hydrochloric acid (12 N). The resulting

5 quinazolinyl)-3-methylurea (5 g.) in 90 ml. of a 25% ethanolic solution of ethylamine is heated at 160° C. for 16 hours. The solvent and excess ethylamine are then evaporated, and the residue is recrystallized from methanol/water to afford the desired product.

EXAMPLE XIII

The procedure of Example XII is repeated using appropriate quinazoline and isocyanate to afford the following compounds:

R ₁	R ₂	R ₃	R ₄	R ₅
(2-C ₄ H ₉ O)-CH ₂ -	H-	CH ₃ -	CH ₃ O-	CH ₃ O-

solution is placed in a porcelain evaporating dish, 1.98 g. (0.33 mole) of ammonium cyanate is added, and the mixture is heated on the steam bath for 1 hour. The liquid is allowed to cool, set aside at room temperature for 1 hour, and then evaporated slowly to dryness over a period of 2-3 hours. The crystalline residue is crushed finely, 30 ml. of water is added, and again the mixture is evaporated slowly. The residual powder is heated finally on the steam bath for 4-5 hours.

The resulting mixture of crude product and ammonium chloride is powdered finely and suspended in 30 ml. of water. The mixture is warmed slowly to 70° C. with mechanical stirring, then allowed to cool to 35° C. and the product is filtered with suction.

EXAMPLE XI

The procedure of Example X is repeated using an equivalent amount of appropriate quinazoline to afford the following products

Z	R ₃	R ₄	R ₅
1-piperazinyl	CH ₃ -	CH ₃ O-	CH ₃ O-
4-hydroxyethyl-1-piperazinyl	CH ₃ -	Same	Same
4-hydroxyethyl-1-piperazinyl	n-C ₄ H ₉ -	do	H-
4-β-hydroxyethyl-1-piperidino	CH ₃ -	H-	CH ₃ O-
4-hydroxy-1-piperidino	CH ₃ -	CH ₃ O-	Same
2-β-hydroxyethyl-1-piperidino	CH ₃ -	Same	Do.
4-(4-hydroxybutyl)-1-piperidino	C ₂ H ₅ -	H-	Do.

EXAMPLE XIV

(2-ethylamino-6,7-dimethoxy-4-quinazolinyl)urea

To a suspension of 2-chloro-4-amino-6,7-dimethoxyquinazoline (6.2 g., 0.03 mole) in 30 ml. of warm water is added, with stirring, 2.75 ml. (0.33 mole) of concentrated hydrochloric acid (12 N). The resulting solution is placed in a porcelain evaporating dish, 1.98 g. (0.33 mole) of ammonium cyanate is added, and the mixture is heated on a steam bath for one hour. The liquid is allowed to cool, set aside at room temperature for one hour, and then slowly evaporated to dryness over a period of 2-3 hours. The crystalline material is crushed finely, 30 ml. of water is added, and again the mixture is evaporated slowly. The residual powder is heated on a steam bath for an additional 4-5 hours, after which time it is finely powdered and again suspended in 30 ml. of water. The mixture is warmed slowly to 70° C. with stirring, then allowed to cool to 35° C. The resulting (2-chloro-6,7-dimethoxy-4-quinazolinyl)urea is collected by filtration.

A suspension of the (2-chloro-6,7-dimethoxy-4-quinazolinyl)urea (5 g.) in an ethanolic solution of ethylamine is heated at 160° C. for 16 hours. The solvent and excess ethylamine are then evaporated, and the residue is recrystallized from methanol/water to afford the desired product.

R ₁	R ₂	R ₄	R ₅
C ₆ H ₅ -	C ₆ H ₅ -	CH ₃ O-	CH ₃ O-
CH ₂ -CH-CH ₂ -	CH ₂ -CH-CH ₂ -	H-	C ₂ H ₅ O-
CF ₃ CH ₂ -	CF ₃ CH ₂ -	CH ₃ O-	CH ₃ O-

EXAMPLE XII

1-(2-ethylamino-6,7-dimethoxy-4-quinazolinyl)-3-methylurea

To a solution of 2-chloro-4-amino-6,7-dimethoxyquinazoline (6.2 g., 0.03 mole) in 120 ml. of toluene was added methyl isocyanate (6.84 g., 0.12 mole) and catalytic quantity of pyridine. The mixture is heated in a pressure vessel at 120° C. for 12 hours, and the resulting 1-(2-chloro-6,7-dimethoxy-4-quinazolinyl)-3-methylurea is collected by filtration and is recrystallized from ethanol.

A suspension of the 1-(2-chloro-6,7-dimethoxy-4-

11
EXAMPLE XV

The procedure of Example XIV is repeated using appropriate quinazolines to afford the following compounds:

R ₁	R ₂	R ₄	R ₅
C ₆ H ₅ CH ₂ — HOCH ₂ CH ₂ — H—	H— HOCH ₂ CH ₂ — H—	H— CH ₃ O— Same—	C ₂ H ₅ O— CH ₃ O— Same—

EXAMPLE XVI

Pharmaceutically-acceptable salts

The hydrochloric acid addition salts of the products of Examples I-XII are prepared by mixing an alcoholic solution of each of said products with dilute hydrochloric acid and evaporating the resulting solution to dryness.

Additional acid addition salts of each of these products are similarly prepared by using aqueous solutions of the following acids in place of said hydrochloric acid: hydrobromic acid, hydriodic acid, nitric acid, sulfuric acid, citric acid, phosphoric acid, maleic acid, tartaric acid and lactic acid.

EXAMPLE XVII

Anti-hypertensive activity

Hypotensive activity was measured in hypertensive conscious dogs with systolic blood pressure of at least 150 mm. Hg. The hypertension was induced by the method of Goldblatt et al., J. Exp. Med. 59, 347 (1934).

The systolic blood pressure was determined on the coccygeal artery according to the method of Prioli and Wynbury, J. Appl. Physiol. 15, 323 (1960) prior to drug administration and 2, 6 and 24 hours thereafter. The drugs were administered orally in the form of capsules, except as indicated.

The following hypotensive effects were noted:

	Dosage, mm./kg.	Blood pressure decrease mm. Hg.
Dimethylamino	10	33
4-(2-furoyl)-1-piperazinyl	30	20
4-allyl-1-piperazinyl	40	30
4-carbisobutoxy-1-piperazinyl ¹	40	30

¹ Aqueous suspension.

What is claimed is:

1. Compounds of the formulae

12

wherein

R₁ and R₂ are each selected from the group consisting of hydrogen, alkyl having from 1 to 5 carbon atoms, alkenyl having from 3 to 5 carbon atoms, hydroxyalkyl having from 2 to 5 carbon atoms, phenyl, benzyl, phenylethyl, 2-furfuryl, 2,2,2-trifluoroethyl and cycloalkyl having from 3 to 8 carbon atoms;

R₃ is H or alkyl having from 1 to 6 carbon atoms;

R₄ and R₅ are each selected from hydrogen and alkoxy having from 1 to 3 carbon atoms, at least one of R₄ and R₅ being alkoxy;

Z is selected from the group consisting of morpholino, 1-azacycloheptyl, 1-azacyclooctyl and piperazine of the formula:

where Y is selected from the group consisting of hydrogen, alkyl having from 1 to 5 carbon atoms, hydroxyalkyl where alkyl has from 2 to 5 carbon atoms, alkanoyl having from 2 to 7 carbon atoms, allyl, propargyl, 2-methylallyl, phenyl, benzyl, benzoyl, halo-benzoyl and halophenyl where halo is chloro or bromo, trifluoromethylphenyl, methoxyphenyl, methylphenyl, methylbenzoyl, methoxybenzoyl, trifluoromethylbenzoyl, furoyl, benzofuroyl, thenoyl, pyridinecarbonyl, 3,4,5-trimethoxybenzoyl, carboxylic acid alkyl ester where alkyl has from 1 to 6 carbon atoms, carboxylic acid alkenyl ester where alkenyl has from 3 to 6 carbon atoms;

30 piperidino of the formula:

where X' is hydrogen or phenyl, and X is selected from the group consisting of hydrogen, alkyl having from 1 to 5 carbon atoms, alkoxy having from 1 to 4 carbon atoms, hydroxy, hydroxyalkyl where alkyl has from 2 to 5 carbon atoms, phenyl, and benzyl when X' is hydrogen, and X is carboxylic acid alkyl ester where alkyl has from 1 to 6 carbon atoms when X' is phenyl; and the hydrofluoric acid and perchloric acid addition salts thereof, and the pharmaceutically acceptable mineral acid and organic acid addition salts thereof.

2. Compounds of claim 1 wherein R₄ and R₅ are each methoxy.

3. The compound of claim 1 of Formula I wherein R₁, R₂ and R₃ are each methyl and R₄ and R₅ are each methoxy.

4. The compound of claim 1 of Formula II wherein R₃ is methyl, R₄ and R₅ are each methoxy, and Z is 4-(2-furoyl)piperazin-1-yl.

5. The compound of claim 1 of Formula II wherein R₃ is methyl, R₄ and R₅ are each methoxy and Z is 4-allylpiperazin-1-yl.

6. The compound of claim 1 of Formula II wherein R₃ is methyl, R₄ and R₅ are each methoxy and Z is 4-carbisobutoxypiperazin-1-yl.
